(57) **CLAIM**

The ornamental design for a counterweight for a backhoe loader, as shown and described.

DESCRIPTION

FIG. 1 is a front, left-side, and top view of a counterweight for a backhoe loader showing one embodiment of the new design.

FIG. 2 is a top plan view of the counterweight for a backhoe loader.

FIG. 3 is a front elevation view thereof.

FIG. 4 is an enlarged left-side elevation view thereof.

FIG. 5 is an enlarged right-side elevation view thereof.

FIG. 6 is a front, right-side, and top view thereof; and, FIG. 7 is a front, left-side, and top view of a counterweight for a backhoe loader showing the placement of the counterweight on the hood of a backhoe loader.

The broken lines show environmental structure and form no part of the claimed design.

Any elements that are not clearly disclosed are not part of the claimed design.

1 Claim, 6 Drawing Sheets
